Attorney

UNITED STATES PATENT OFFICE

SCHUYLER C. HULETT, OF SPOKANE, WASHINGTON

BOILER FEEDER

Application filed March 25, 1929. Serial No. 349,801.

My present invention relates to improvements in boiler feeders for supplying water to the boiler under steam boiler pressure and for automatically controlling the feed of water to the boiler. While the apparatus of my invention is applicable for use with various types of boilers, it is especially designed for use with the steam boilers of clothes pressing machines used in laundries, dry cleaning 5 establishments, and other places, for pressing garments of personal wear.

The water feed apparatus is of the type utilizing a float actuating device controlled by the level of the water in the boiler, in combination with electrically operated control valves located in a circuit or circuits that includes a duplex switch mechanism operated by the float actuating mechanism, to make and break the circuits for the operation 10 of the valves.

The invention consists in certain novel combinations and arrangements of parts as will hereinafter be more fully set forth and claimed. In the accompanying drawings I 15 have illustrated one complete example of the physical embodiment of my invention wherein the parts are combined and arranged according to the best mode I have thus far devised for the practical application of the 20 principles of my invention.

Figure 1 is an exterior view of a portion of a boiler equipped with the mechanism of my invention. Figure 2 is a top plan view of the snap device forming part of one of the 25 stationary contact members of the switches. Figure 3 is an enlarged view partly in vertical section of the float control and switch mechanism. Figure 4 is an electrical diagram of parts in the apparatus. Figure 5 is a broken sectional view of the feed tank with steam and water pipes and valves therefor. Figure 6 is a side view showing a portion 30 of the upper one of the duplex switches.

In Figure 1, showing the general assembly 45 of parts, the boiler 1 is shown provided with a feed water tank 2 supported from the boiler as by brackets 3 and located near the top of the upright boiler. A water gage tube 4, and steam gage 5 for the boiler are illustrated, and the water supply for the feed

tank is provided from a suitable source through pipe 6. A steam pipe 6' is extended from the dome of the boiler and provided with a check valve 7, a hand valve 9, and an electrically operated control valve 11 from 55 which latter valve the steam pipe 11' projects into the top of the water tank 2.

The water supply pipe 6 is provided with a check valve 8, and a hand control valve 10 is interposed between the steam pipe 6' and the water pipe 6, and normally closed. The water pipe is provided with an electrically controlled valve 12 and a U-shaped inlet feed pipe 13 located within the water tank with its mouth terminating just beneath the top 60 of the tank.

The water is fed to the boiler from the tank through a feed pipe 14 extending from the bottom of the tank to the boiler, and equipped with a hand control valve 15 and a check valve 16, the latter opening toward the 65 boiler.

For preheating the water in the water tank, with the valve 12 closed, and 7, 9, and 10 open, steam may be introduced through 70 the U-shaped inlet pipe 13 that is submerged in the water of the tank.

For automatically controlling the supply of water to the water tank and the supply of steam to the tank the two control valves 11 and 12 are provided with solenoid magnets 75 and 18, and these magnets are included in electrical circuits. The circuits include duplex switches, indicated as a whole by the numbers 25 and 26 in Figure 3, and these switches are opened and closed, or the circuits made and broken through the action of a float control mechanism governed by the 80 water level in the tank and gage 4.

The float control device comprises a float 85 tank 19 that communicates at its upper and lower ends with the gage tube 4, and a float 20 of suitable type, within the tank has a threaded stem 21 which projects from the tank through a suitable packed joint into the housing 22 in which the switches 25 and 26 are enclosed. These switches are included 90 in the solenoid circuit as 23 which receives energy from a suitable source which may be a battery 24.

The switches 25 and 26 are of similar construction and act with a spring or snap action in opening or closing the control valve circuits. The movable member of a switch includes an arm 27, and conductor plate 28 to which one of the electrical wires is attached, the arm and plate being carried on the stem 21. Above the arm and plate a conductor head or bushing 29 and an insulated bushing 30 are carried on the stem, and the arm, plate and bushings or heads are clamped on the stem by nuts 31.

The stationary members of the switch, which include resiliently supported or spring actuated snap devices, include an upright bar 32 pivoted within the housing at 33 on an insulated bracket 34, and a spring 35 is coiled about the pivot members to urge the upright bar toward the stem 21. As best seen in Figure 6 the upright bar passes through a guide slot 36 in the arm 27 and the movement of the upright bar is limited thereby.

At the free end of the pivoted, upright bar is carried a spring or snap device in the form of a pivoted and hinged frame that includes pairs of links 37 and 38 that are pivoted together on the bar 32 at 39, and the links 38 are pivotally anchored at 40 to the supporting arm 27 of the float-stem 21. The free end of this snap frame carries the contact roller 41 which is journaled in the ends of the links 37, and this roller, as seen in Figure 6 is designed to roll from the contact head 29 to the insulated or non-conducting head or bushing 30; with a snap action when the circuit is broken. In Figure 3, the two rollers 41, one of which is attached to the upper and the other to the lower snap device, are in contact with the non-conducting or insulated heads of the float controlled switches, and the circuit is broken. The heads are curved as shown to accommodate the rollers and to prevent excessive movement or displacement of the rollers from the heads.

The snap frames are provided with pairs of springs 42 that connect the outer extremities of the pairs of links and as the supporting arm 27 moves with the stem in relation to the bar 32 the pivoted frame is flexed, with its central pivot 39 passing across the line of the tension of the springs 42, thereby snapping the roller from a conductor head to a non-conductor head or vice versa as the circuit maker is opening or closing, and of course the springs retain the roller in its adjusted position.

For priming the boiler or for emergency use I may provide an emergency supply tank 43 that is connected to the water tank 2 by a pipe 44 having a control valve 45, and an overflow pipe 46 from the main water tank to the emergency tank is provided with a control valve 47 for use in disconnecting the parts.

Assume that the desired level of the water

in the boiler is as shown in Figure 3. Should it drop to a point near the bottom of the glass, it follows that the float 20 will also drop, it being supported by the water surface. This causes stem 21 to descend carrying with it the arms 27, also the contact heads 29 and insulated heads 30, this action causing the heads 30 to push down on rollers 41, and at the same time the arm 27 pulls link 38 down. When the pin in roller 41, and the pin 40 in link 38 reach a level lower than the stationary pin 39, the springs 42 act to accelerate the movement of the roller, whence it moves to the contact head with a jerk. The circuit is now closed and the solenoid magnets 17 and 18 are energized, whence they open valves 11 and 12, thus allowing water to enter tank 2 through pipe 13, and steam to enter through pipe 11. The steam forces the water out through valve 15 which is normally open, through pipe 14 and check valve 16 into the boiler, thus causing the water to rise until the float 20 causes a reverse action of the snap devices and thus breaks the circuit again whence the solenoids are de-energized and their valves 11 and 12 close by spring action, shutting off the steam and water.

Having thus fully described my invention, what I claim as new and desire to secure by Letters Patent is:—

1. In a float controlled and electrically operated boiler feed mechanism, the combination with a float-stem, an arm carried thereby, a conducting head and a non-conducting head secured with the arm to the stem, of a pivoted snap frame pivotally anchored to the arm, and a contact member carried at the free end of said snap frame.

2. In a float controlled and electrically operated boiler feed mechanism, the combination with a float stem, an arm, a conducting head, and a non-conducting head carried by said stem, of a snap frame comprising a stationary pivoted supporting bar, a pivotal connection between the frame and arm, a spring connecting the extremities of the snap frame, and a contact roller carried at the free end of said frame.

3. The combination with a float-stem and a housing, of a pair of spaced arms carried by the stem, a conducting head and an insulated head adjacent each arm, a pair of oppositely pivoted bars supported within the housing, a flexible snap frame pivotally anchored to each arm, a contact roller at the free end of each frame, and each said snap frame having a central pivotal connection to the free end of a pivoted bar.

In testimony whereof I affix my signature.

SCHUYLER C. HULETT.
